M. K. CARR

COUPLING FOR RAILWAY CARS

Filed June 16, 1921

UNITED STATES PATENT OFFICE.

MELVIN K. CARR, OF BREMERTON, WASHINGTON.

COUPLING FOR RAILWAY CARS.

Application filed June 16, 1921. Serial No. 477,988.

To all whom it may concern:

Be it known that I, MELVIN K. CARR, a citizen of the United States, and a resident of Bremerton, in the county of Kitsap and 5 State of Washington, have invented certain new and useful Improvements in Couplings for Railway Cars, of which the following is a specification.

The present invention relates to an improvement in couplings for railway cars or the like and has for its object to provide a device of this character which is of simple and durable construction, reliable in operation, and easy and inexpensive to manufacture, which is adapted to effect the automatic and efficient coupling of the railway car or other vehicles to be coupled and which may be released without necessity of the operator going between the cars or vehicles. 10 Other objects and advantages of the invention reside in certain novel features of construction, combination and arrangement of parts which will be hereinafter more fully described and particularly pointed 15 out in the appended claims, reference being had to the accompanying drawings forming part of this specification, and in which:

Figure 1 is a view in side elevation of the coupling members immediately prior to the 20 coupling action, parts being shown in section for the sake of illustration;

Figure 2 is a view in vertical longitudinal section, showing the parts coupled, parts being shown in elevation for the sake of 25 illustration;

Figure 3 is similar view in horizontal section;

Figure 4 is a detail perspective view of one 30 of the swinging coupling bars and associated 35 elements.

Referring to the drawings wherein for the sake of illustration is shown the preferred embodiment of the invention, the character C designates the coupling members 40 which are carried by the cars in the usual manner and which are oppositely arranged and of identical construction so that a description of one will serve for both.

Each coupling member includes a housing 45 10 preferably of frusto-conical form and carried at the lower end of the draw bar in the usual manner. The housing is provided with a removable plate 11 normally secured in position by fastening means 12 or the

like. In each housing there is provided a 55 chamber 13 having vertical side walls 14 constituting guides.

A vertically swinging coupling bar 15 is operatively arranged in the housing and has a flat vertical face 15^a engaged with the 60 guide face 14 of the housing to constrain the coupling bar to its proper motion. At its inner end the coupling bar is provided with an enlarged bearing 16 having its lateral face flat as indicated at 65 16^a and also engaged with the guide walls 14 of the chamber to supplement the action of the face 15^a and wall 14 in constraining the swinging bar to provide motion. Trunnions 17 undercut, as at 17^a are 70 carried by the bearing 16 and are journaled in the walls of the housing, these walls being suitably constructed for this purpose. A hook 18 is provided at the outer end of the coupling bar and includes a bill 19 having 75 a curved outer face 19^a. The coupling bar 15 is provided with a seat 20 adjacent and to the rear of the bill of the hook 18. A lock lug 21 is carried by the coupling bar intermediate the bearing 16 and the hook 18 and is 80 provided with an inclined or cam surface 22 cooperable with the curved face 19^a of the bill 19 of the hook of the complementary coupling member. At the upper end of the lock lug an inclined shoulder 23 is provided 85 and is adapted to be received in the seat 20 of the latch bar of the complementary member when the coupling members are associated in coupled relation, as clearly shown in Figure 2. 90

Operating means is provided and preferably comprises a control lever 25 rotatably mounted upon the car and having a crank arm 26 connected by a chain or other flexible element 27 with a link 28 which in turn is 95 pivotally connected to the latch bar of the underlying coupling member, as clearly shown in Figure 2.

In the coupling operation each projecting end of each coupling bar of each coupling member enters the housing of the other coupling member and the curved faces 19^a of the bills of the hooks thereof ride up the cam surfaces 22 of the lock lugs 21. This carries the bills of the hooks over the lock 100 lugs so that they then are disposed slightly behind and are adapted to engage the rear faces of the lock lugs and so that the in- 105

clined shoulders then are received in the seats 20. There is thus provided an efficient, effective and secure coupling.

In the coupling operation, either one of the control levers 25 is grasped and rotated to swing the crank arm upwardly and thus draw the link 28 upwardly. The link 28 carries the vertically swinging coupling bar 15 to which it is connected upwardly about its trunnions. This also lifts the other coupling bar and as the coupling bars thus swing, the bills of the hooks are disengaged from the lock lugs and the shoulders of the lock lugs slide out of the seats of the coupling bars and thus disengagement is effected.

I claim:

1. In a coupling of the character described, a pair of coupling members, each including a housing having a chamber therein provided with vertically side walls constituting guides, a coupling bar having a flat lateral face engaging the adjacent side walls of the chamber, trunnions carried by the bar and journaled in the housing for constraining the coupling bar to vertical swinging movement, a hook carried at the outer end of the coupling bar and having a bill provided with a curved outer face, said coupling bar having a seat formed therein adjacent said hook, a lock lug carried by the coupling bar and having a cam adapted to coact with the curved bill of the hook of the complementary

coupling member and an inclined shoulder at its upper end adapted to be received in the seat of the coupling bar of the complementary coupling member, and operating mechanism for releasing said coupling members including a control lever having a crank arm, a link pivotally connected at one end to the coupling bar and a chain connecting said link and said crank arm.

2. In a coupling of the character described, a housing having a chamber, a swinging coupling bar pivoted to said housing within the chamber and projecting therefrom, a hook carried by the outer end of the coupling and having a bill provided with a curved face, said coupling bar having a seat formed therein adjacent said hook, having a cam face and an inclined shoulder at the upper end thereof, and operating means for releasing said coupling.

3. In a coupling of the character described, a housing having a chamber, a swinging coupling bar pivoted to said housing within the chamber and projecting therefrom, a hook carried by the outer end of the coupling and having a bill provided with a curved face, said coupling bar having a seat formed therein adjacent said hook, and a lock lug carried by the coupling bar having a cam face and an inclined shoulder at the upper end thereof.

MELVIN K. CARR.
